WAX MELTING HEATER

Walter Ziegelmaier, 17561 State Road 23,
South Bend 15, Ind.

Filed Apr. 9, 1964, Ser. No. 79,433

Term of patent 14 years

(Cl. D55—1)

FIG. 1

FIG. 2

FIG. 3

FIG. 4

FIG. 5

FIGURE 1 is a perspective view of a wax melting heater, embodying my new design;

FIGURE 2 is a top plan view of the device shown in FIGURE 1;

FIGURE 3 is a front elevational view;

FIGURE 4 is a side elevational view; and

FIGURE 5 is a bottom plan view.

I claim:

The ornamental design for a wax melting heater, substantially as shown.
